(57) **CLAIM**

The ornamental design for a display screen or portion thereof with graphical user interface, substantially as shown and described.

DESCRIPTION

The file of this patent contains at least one drawing/photograph executed in color. Copies of this patent with color drawing(s)/photograph(s) will be provided by the Office upon request.

FIG. 1 is a front view of a display screen or portion thereof with a graphical user interface showing a first embodiment of the claimed design.

FIG. 2 is a second embodiment thereof.

FIG. 3 is a third embodiment thereof.

FIG. 4 is a fourth embodiment thereof.

FIG. 5 is a fifth embodiment thereof.

FIG. 6 is a sixth embodiment thereof.

FIG. 7 is a seventh embodiment thereof.

FIG. 8 is an eighth embodiment thereof.

FIG. 9 is a ninth embodiment thereof; and,

FIG. 10 is a tenth embodiment thereof.

The broken lines in the figures show a display screen or portion thereof, and form no part of the claimed design.
